UNITED STATES PATENT OFFICE.

EDWARD A. COWLES, OF WILKINSBURG, PENNSYLVANIA.

CHUCK.

No. 800,272.

Specification of Letters Patent.

Patented Sept. 26, 1905.

Application filed November 25, 1904. Serial No. 234,212.

To all whom it may concern:

Be it known that I, EDWARD A. COWLES, a resident of Wilkinsburg, in the county of Allegheny and State of Pennsylvania, have invented a new and useful Improvement in Chucks; and I do hereby declare the following to be a full, clear, and exact description thereof.

My invention relates to chucks such as are used on lathes, boring-mills, milling-machines, drilling-machines, and other metal and wood working machines.

My invention relates especially to that type of chucks having a number of radially-movable jaws, together with means for moving all said jaws simultaneously, and which are ordinarily known as "universal" chucks, and also that type of chucks having a number of radially-movable jaws, together with means for moving all said jaws either simultaneously or independently, and which are ordinarily known as "combination-chucks."

The object of my invention is to improve chucks of this character by providing simple, cheap, and easily-applied means for holding in place the jaw-actuating pinion or pinions, this means comprising a key engaging shoulders on the pinion and on the chuck-body and held in place by means of the backing-plate 30 of the chuck.

In the accompanying drawings, Figure 1 is a face view of a lathe-chuck constructed substantially according to my invention. Fig. 2 is a vertical section of the same on the line 2, Fig. 1. Fig. 3 is a side view of the actuating-pinion, and Fig. 4 shows side and edge views of the pinion-retaining key.

My invention may be applied to any form of universal or combination chuck. In the drawings it has been shown applied to a lathe-chuck; but this has been selected for purposes of illustration merely.

The chuck-body, which is a solid piece, is shown at 1, and this is provided on its front face with a series of radial ways 3, in which are mounted the jaws 4. These jaws may be of any suitable or desirable form, those shown being of the reversible type having gripping-faces on both ends and having the faces on 50 one end stepped, as clearly shown in Fig. 2.

The several jaws have been shown as independently adjustable; but this is no part of my invention. They are shown as provided with threaded bottom faces which are engaged by screws 6, mounted in jaw-carriers 7. These jaw-carriers are movable radially in the

ways 3 and are provided on their bottom faces with teeth 8, which are engaged by a scroll-gear 9, mounted in an annular recess 10, formed in the rear face of the chuck-body. 60 As far as the present invention is concerned the teeth 8 might be formed directly on the bottom faces of the jaws and the carriers 7 entirely dispensed with.

The scroll-gear 9 is provided on its lower 65 or outer face with teeth 11, which are engaged by actuating-pinions 12. One such pinion 12 is sufficient; but preferably two or more will be employed for the purpose of balancing the chuck and convenience in using, three being 70 shown in the drawings.

The actuating-pinions are each provided on their inner ends with a journal 13, which projects into a suitable seat or bearing formed in the chuck-body and serves as a bearing to take 75 up inward thrust. At their outer ends the gears are each provided with an enlarged journal 14, having a bearing in an opening formed in the outer shell or rim 15 of the body. These gears at their outer ends are 80 provided with suitable means whereby they can be rotated, such as the polygonal socket 16 for receiving a key or wrench. It will be obvious that by turning any one of the pinions 12 the scroll-gear 11 will be rotated, and 85 thus move the jaws simultaneously inwardly or outwardly. My invention has for its object to provide simple and cheap means for retaining the pinions 12 in place. To this end the pinions are provided just inside of the 90 shell 15 of the body with necks or shoulders 17. Inserted between the shoulders thus formed on the gears and the inner face of the body-shell are suitable retaining-keys 18, which may be of various forms, but which 95 preferably will be of U shape, as shown in Fig. 4, so as to form a bearing for the shoulder 17 and against the inner face of the body-rim 15 for the greater portion of the circumference of the gear and of the opening in the 100 body-rim. Inasmuch as the body is open on its rear, these retaining-keys can be easily slipped in place. They will be held from falling out by means of the backing-plate 19, which is provided on all such forms of chucks 105 in order to keep dirt from getting into the cavity of the chuck-body.

The retaining-keys are very simple and cheap of construction and can be more readily applied or removed than prior retaining devices. The cost of constructing the chuck is therefore materially decreased, and, further-

more, greater facility and ease of changing the pinions is provided for.

What I claim is—

1. In a chuck, the combination of a body 5 provided on one face with ways and having an annular cavity in its opposite side and having the central and rim portions on said face integral with the body, jaws mounted in said ways, a scroll-gear mounted in the annular 10 cavity and engaging said jaws, and a pinion engaging said scroll-gear and projecting into an opening in the rim of the body, said gear having a bearing in said rim and in the integral central portion of the body, and a key 15 engaging shoulders on the pinion and on the chuck-body and serving to prevent displacement of said pinion.

2. In a chuck, the combination of a body provided on one face with ways and having an 20 annular cavity in its opposite face and having the central and rim portions on said face integral with the body, jaws mounted in said ways, a scroll-gear mounted in the annular cavity and engaging said jaws, a pinion engaging 25 the scroll-gear, said pinion projecting into an opening in the rim of the chuck-body and having a bearing in said rim and in the integral central portion of the body, and being provided with an annular shoulder, and a U- 30 shaped key held in the chuck-body and engaging said annular shoulder and serving to prevent displacement of said pinion.

3. In a chuck, the combination of a body provided on one face with ways and having an 35 annular cavity in its opposite face, jaws mounted in said ways, a scroll-gear mounted in the annular cavity and engaging said jaws and serving to move the same, a pinion also mounted in the annular cavity and engaging the 40 scroll-gear for rotating the same, said pinion projecting into an opening in the rim of the chuck-body and being provided with an annular shoulder, a U-shaped key between the annular shoulder of said pinion and the rim 45 of the chuck-body, and a backing-plate clos-

ing the annular cavity in the chuck-body and serving to retain the key in place.

4. In a chuck, the combination of a body provided on one face with ways and having an annular cavity in its opposite face, jaws mounted 50 in said ways, a scroll-gear in the annular cavity and engaging said jaws, a pinion engaging the scroll-gear for rotating the same, said pinion projecting into an opening in the rim of the chuck-body and being provided 55 with an annular shoulder, a key between the annular shoulder on said pinion and the rim of the chuck-body, and means for retaining the key in place.

5. In a chuck, the combination of a body 60 provided on one face with ways and having an annular cavity in its opposite face, jaws mounted in said ways, a scroll-gear in the annular cavity and engaging said jaws, a pinion mounted in the annular cavity and engaging the 65 scroll-gear, said pinion projecting into an opening in the rim of the chuck-body and being provided with an annular shoulder, a U-shaped key engaging said annular shoulder and the rim of the chuck-body, and means for 70 retaining said key in place.

6. In a chuck, the combination of a body provided on one face with ways and having an annular cavity in its opposite face, jaws mounted 75 in said ways, a scroll-gear mounted in the annular cavity and engaging said jaws, a pinion also mounted in the annular cavity and engaging the scroll-gear, said pinion projecting into an opening in the rim of the chuck-body and being provided with an annular 80 shoulder, a key between said annular shoulder and the rim of the chuck-body, and a backing-plate closing said annular cavity and serving to retain the key in place.

In testimony whereof I, the said EDWARD 85 A. COWLES, have hereunto set my hand.

EDWARD A. COWLES.
